METALLIC WINDOW STRUCTURE

Adolf H. Schaffert, Youngstown, Ohio, assignor
to Truscon Steel Company, Youngstown, Ohio,
a corporation of Michigan

Application May 16, 1930. Serial No. 453,040

4 Claims. (Cl. 189—75)

The object of the present invention is to provide a metallic window structure in which the guideways for the sash are effectively maintained against accidental variation.

5 With the structure now in general use, it has been found that the parts of which the window frame is made, are subject by reason of the jars and pressures against them, to creep out of position, thereby opening up the guideways with 10 consequent unoccupied space through which infiltration of air can take place. The present structure is designed to obviate these difficulties.

In the accompanying drawings:

Figure 1 is a vertical sectional view through 15 a window frame, embodying the present invention.

Figure 2 is a horizontal sectional view showing portions of the sashes in section.

Figure 3 is a sectional view of the parting strip 20 and a portion of the guide structure showing the method of securing the parting strip.

In the embodiment disclosed the frame of the window includes a top member 3, a sill member 4, and side members 5.

25 Each side member consists of a box formed of sheet metal having a rear wall 6, an inner side wall 7 and an outer side wall 8 integral with the rear wall 6. The wall 7 terminates in a reversely flanged margin forming a hook 9. The wall 8 preferably has an offset portion 10 with an inset face wall 11 terminating in an inwardly and rearwardly bent flange 12. The portion at said flange constitutes one wall of the sash guideway 13.

35 A cooperating wall section 14 has an inturned flange 15^a forming a hook that interfits with the reverse flange or hook 9 of the box wall 7. This wall 14 has an inwardly and rearwardly turned portion 15 constituting the outer wall of 40 the other guideway 16. The portion 15 is extended into an angular internal wall 17 that overlies an oppositely extending wall 18 having an angular portion 19 suitably fixed in the offset portion 10 of the wall 8. The overlapping portions of the walls 17 and 18 are rearwardly ribbed, so that the wall 18 has in its outer face a longitudinal channel 19^a that receives the rib 20 formed on the rear side of the wall 17. The parts are thereby interfitted or interlocked.

50 A parting strip 20^a is provided that is also of sheet metal and of tubular formation. This strip has a facing wall terminating in doubled flanges 21 from which project rearwardly extending walls 22 having terminal inset flanges 23 55 that rest against the wall 17 on opposite sides

of the rib 20 and channel 19^a in which it is engaged. Fastening screws 24, passing through the facing wall 20^a, also pass through the wall 17 and are threaded into bosses 25 formed on the rear wall 18. The parting strip is therefore 60 securely fastened to the walls 17 and 18, and serves to secure said walls together and insure the interfitting engagement of the ribs 19 and 20. The outstanding flanges 21 constitute the inner walls of the guideways 13 and 16. 65

The window sashes 26, which may be of any desired character, preferably have outstanding guides 27 that respectively operate in the guideways 13 and 16. These guides 27 have suitable springs 28 serving to urge the guides against the 70 walls of the guideways.

The side member structure has been found particularly efficacious in that the parts can be readily assembled and removed, and when in assembled relation, are effectively interlocked so 75 that the distance between the guideways 13 and 16 does not vary nor do the parts creep to leave open spaces at the sides of the sash guides 27. A material amount of air infiltration is thereby 80 prevented.

From the foregoing, it is thought that the construction, operation and many advantages of the herein described invention will be apparent to those skilled in the art without further description, and it will be understood that various 85 changes in the size, shape, proportion and minor details of construction may be resorted to without departing from the spirit or sacrificing any of the advantages.

What I claim, is:

1. In a window-frame, the combination with outer guide members forming the outer walls of spaced guide slots and having portions extending behind the slots and detachably interlocked, of a parting strip between said portions forming 95 the inner walls of the guide slots, and means for securing the parting strip in place and securing the members together in interlocked relation.

2. In a window-frame, the combination with a boxing having an inturned facing wall forming one wall of a guide slot, said boxing having an internal wall extending behind said guide slot, of another and detachable facing wall forming a wall of a second guide slot and having an internal portion overlapping and interlocked with 100 the first internal wall, a parting strip located between the facing walls, and means for securing the parting strip in place.

3. In a window-frame, the combination with a boxing having an inturned facing wall form- 110

ing one wall of a guide slot, said boxing having an internal wall extending behind said guide slot, of another and detachable facing wall forming a wall of a second guide slot and having an internal portion overlapping the first internal wall, one of said overlapping portions having a groove and the other a rib engaged in the groove, a parting strip located between the facing walls, and fasteners securing the parting strip to the 10 overlapped portions of the internal walls and securing the rib in the groove.

4. In a window frame, the combination with outer guide members forming the outer walls of

80 spaced guide slots and having overlapped portions extending behind the slots and provided with a longitudinal interfitting tongue and groove interlock, a parting strip located between the said outer slot walls and forming inner slot walls, said parting strip having rearwardly extending side walls that bear against the overlapped portions on opposite sides of the tongue and groove interlock, and fasteners securing the parting strip to the overlapped portions and being located between the side walls of the parting strip.
